HOSEA H. STRAIT, OF OVERLAND, MISSOURI

PAPER-FEED GUIDE FOR PLATEN PRESSES

Application filed July 3, 1929. Serial No. 375,843.

This invention relates generally to paper guides for printing presses, and more particularly to paper feed guides for platen presses, the predominant object of the invention being to provide an extremely simple, inexpensive, and highly efficient device of this type adapted to be accurately adjusted on a tympan to serve as a stop, or gage, for the sheets of paper transmitted to the tympan.

Fig. 1 is a top or plan view showing three of my guides mounted on a tympan.

Fig. 2 is an enlarged top or plan view of a guide embodying the features of this invention.

Fig. 3 is an enlarged longitudinal section of the guide showing same mounted on a tympan and platen.

Fig. 4 is a view similar to Fig. 3, but illustrating certain parts of the guide in moved positions.

Fig. 5 is a fragmentary perspective showing the manner in which the lever of the guide is hingedly supported.

In the drawing, wherein is shown for the purpose of illustration, merely, one embodiment of the invention, A designates a tympan sheet adapted to be secured to a platen B by means of a tympan drawer C, as illustrated in Fig. 1. G designates in Fig. 1 a plurality of my improved guides, which are secured to the tympan so as to determine the location of the paper to be printed.

Each guide G comprises an abutment flange 1 having a smooth lower edge adapted to engage the tympan sheet A, said abutment flange 1 being a part of a downturned flange 2 which extends from the upper edge of the abutment flange 1 and contacts with the rear face of said abutment flange 1. A flat plate 3 is integrally connected to the lower edge of the downturned flange 2, and this plate extends rearwardly from said lower edge of said flange, as shown in Figs. 3 and 4. The lower edge of the flange 2 is preferably higher than the lower edge of the abutment flange 1 (Figs. 3 and 4), so the flange 2 and plate 3 will not in any way prevent the lower edge of the flange 1 from firmly engaging the top face of the tympan sheet A. At the rearmost end of the plate 3 the same is pro-

vided with a rearwardly and upwardly extended tongue 4, and at a point spaced inwardly from said tongue 4 I provide said plate 3 with an aperture 5. The material of which the plate 3 is formed is bent so the portion 6 of the plate to the immediate rear of the aperture 5 is elevated slightly above the remainder of said plate, the portions of the plate at opposite sides of the elevated portion being in substantially the same vertical plane as the remainder of the plate. This bent arrangement of the plate provides the aperture 5 with height measured from the top face of the plate 3, so that a thin sheet metal tongue 7 may be passed through said aperture when said tongue is arranged in a substantially horizontal plane, as shown in Figs. 3 and 4. The flanges 1 and 2 are provided with registering apertures 8 through which the tongue 7 extends.

9 designates the supporting element of the guide, which comprises a blade 10 having a tapered or sharpened forward end 11, an upstanding rear wall 12 formed integral with said blade, and forwardly extended side arms 13 formed integral with said rear wall 12. The side arms 13 at their forward ends are provided each with an aperture 14, and the rear wall 12 is provided with an aperture 15 through which the rearwardly extended portion of the tongue 4 extends, the upwardly extended portion of the tongue 4 being arranged in contact with the rear face of the rear wall 12.

16 designates a gripping lever which is pivotally mounted between and supported by the side arms 13, said lever preferably comprising a substantially L-shaped piece of material having extensions 17 formed at the opposite sides thereof, which are extended into the apertures 14 formed in the side arms 13 so as to cause the gripping lever 16 to be pivotally supported by said side arms. The gripping lever includes a short arm 18 and a longer arm 19 which serves as a handle, and said short arm 18 is notched as indicated at 20. The top edge of the rear wall 12 of the supporting element 9 is notched as indicated at 21, this notch being intended for a purpose to be hereinafter referred to.

In applying my improved guide to the platen of a press the tympan sheet A of said platen is provided with a slit such as that indicated by the reference character 22 in Figs. 2, 3, and 4, and the blade 10 of the supporting element 9 of the guide G is passed through said slit so that said blade is disposed between the platen B and the tympan sheet A associated with said platen. At the time of the application of the guide to the tympan sheet A, the gripping lever 16 and the plate 3 and flanges 1 and 2 are in the positions in which they are shown in Fig. 4.

The blade 10 being disposed beneath the tympan sheet A, the long arm 19 of the gripping lever is moved in an arc of a circle about the pivotal points provided where the extensions 17 pass through the apertures 14 in the side arms 13, and such movement will cause the outer edge of the short arm 18 of the gripping lever to engage the plate 3 as said short arm moves downwardly in an arc of a circle, whereby said plate 3 is moved downwardly into close contact with the top face of the tympan sheet A. When the plate 3 has been moved downwardly as described, the tympan sheet A will be tightly gripped between said plate 3 and the blade 10 of the supporting element 9, whereby the guide G is securely fastened to said tympan sheet. If desired, the top face of the blade 10 may be roughened so as to more firmly grip the tympan sheet. When the gripping lever 16 is in the position in which same is shown in Fig. 3, the outer portion of the arm 19 thereof lies within the notch 21 at the upper edge of the rear wall 12 of the supporting element 9, whereby transverse movement of said arm 19 is prevented.

When the gripping lever 16 is moved to the gripping position as shown in Fig. 3, some downward pressure is felt at the rear portion of the plate 3, and this downward pressure will subject the tongue 7 to friction, whereby accidental movement thereof will be prevented. However, this friction is not sufficiently great to lock the tongue against intentional movement, hence said tongue may be grasped and moved longitudinally as desired. Due to the presence of the notch 20 in the outer edge 50 of the short arm 18 of the gripping lever 16, no pressure is applied to the tongue 7 by said gripping lever.

An important feature of this invention resides in its great simplicity of construction and the consequent ease of assembling the guide, said guide comprising only four parts, namely, the supporting element 9, the plate 3 with its associated flanges 1 and 2 and tongue 4, the gripping lever 16, and the thin metal tongue 7. In assembling the guide, all that need be done is to pass the tongue 4 through the aperture 15 in the rear wall 12 of the supporting element 9, after which the side arms 13 are spread slightly and the gripping lever 60 mounted in place by passing the extensions 17

on said gripping lever through the apertures 14 at the ends of said side arms. The thin sheet metal tongue 7 is then passed through the apertures 8, 5, and 15, and the guide is ready for use.

With a plurality of the guides G secured to the tympan sheet of a platen, the sheets being printed (one of which is indicated at 23 in Figs. 1, 2, and 3) are moved into contact with the abutment flanges 1 of said guides at points beneath the tongues 7, whereby said sheets will be properly positioned for the printing operation.

I claim:

1. A feed guide comprising a supporting element including an upstanding rear wall and provided with a blade adapted to pass through a tympan sheet, side arms formed on said supporting element, a member provided with an abutment, said member being loosely connected to said supporting element by means of a tongue formed thereon which is extended through an aperture formed in said upstanding rear wall of said supporting element, and a gripping lever pivotally attached to said side arms and adapted to contact with a portion of said member whereby said member is forced toward said blade.

2. A feed guide comprising a supporting element provided with a blade adapted to pass through a tympan sheet, side arms formed on said supporting element, a member provided with an abutment, said member being loosely connected to said supporting element, a gripping lever pivotally attached to said side arms and adapted to contact with a portion of said member whereby said member is forced toward said blade, and a longitudinally adjustable tongue supported in apertures formed in said abutment and said supporting element, said tongue being extended through an aperture formed in said member and said member being bent at said opening to provide an opening of greater height than the thickness of the material of which said member is formed.

3. A feed guide comprising a supporting element provided with a blade adapted to pass through a tympan sheet, side arms formed on said supporting element, a member provided with an abutment, said member being loosely connected to said supporting element, a gripping lever pivotally attached to said side arms and adapted to contact with a portion of said member whereby said member is forced toward said blade, and a longitudinally adjustable tongue supported in apertures formed in said abutment and said supporting element, said tongue being extended through an aperture formed in said member, and said member being shaped to provide a raised portion immediately adjacent to said aperture beneath which said tongue passes whereby said member is provided with an opening of greater height than the thickness of the material of which said member is formed.

height than the thickness of the material of which said member is formed.

4. A feed guide comprising a supporting element including an upstanding rear wall and provided with a blade adapted to pass through a tympan sheet, side arms formed on said supporting element, a member provided with an abutment, said member being loosely connected to said supporting element by means of an upwardly bent tongue formed thereon which is extended through an aperture formed in said upstanding rear wall of said supporting element, a gripping lever pivotally attached to said side arms and adapted to contact with a portion of said member whereby said member is forced toward said blade, and a longitudinally adjustable tongue supported in apertures formed in said abutment and said supporting element, said gripping lever being provided with a notch through which said tongue is extended.

5. A feed guide comprising a supporting element including an upstanding rear wall and provided with a blade adapted to pass through a tympan sheet, side arms formed on said supporting element, a member provided with an abutment, said member being loosely connected to said supporting element by means of upwardly bent tongue formed thereon which is extended through an aperture formed in said upstanding rear wall of said supporting element, a gripping lever pivotally attached to said side arms and adapted to contact with a portion of said member whereby said member is forced toward said blade, and a longitudinally adjustable tongue supported in apertures formed in said abutment and said supporting element, said gripping lever being provided with a notch through which said tongue is extended, and said supporting element being provided with a notch in which a portion of said gripping lever rests when said gripping lever is in the gripping position.

45 In testimony that I claim the foregoing I hereunto affix my signature.

HOSEA H. STRAIT.
